CLAIM

The ornamental design for a grille assembly for an automobile, as shown and described.

DESCRIPTION

FIG. 1 is a perspective view of an ornamental design for a grille, insert pair, and light pair applied to an automobile, showing our new design;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawings illustrate portions of the grille assembly for an automobile that form no part of the claimed design.
